UNITED STATES PATENT OFFICE.

JOSEPH WOOD, OF EVERETT, MASSACHUSETTS.

HANDSAW.

1,113,591.

Specification of Letters Patent. Patented Oct. 13, 1914.

Application filed March 4, 1914. Serial No. 822,341.

To all whom it may concern:

Be it known that I, JOSEPH WOOD, a citizen of the United States, and a resident of Everett, in the county of Middlesex and State of Massachusetts, have invented certain new and useful Improvements in Handsaws, of which the following is a specification.

This invention relates especially to a hand saw for the use of butchers, the saw comprising a frame, a saw blade and mechanism for straining the blade to fit it for use and for loosening the blade to permit its removal.

15 The invention has for its object to provide an improved construction enabling the blade to be quickly tightened and loosened and providing a saw which is suitably strong, simple and durable.

20 The invention consists in the improvements which I will now proceed to describe and claim.

Of the accompanying drawings forming a part of this specification: Figure 1 represents a side view of a saw embodying my invention, the blade being strained; Fig. 2 represents a side view of a portion of the saw, the blade being loosened and a part of the handle being broken away; Fig. 3 represents a section on line 3—3 of Fig. 1; Fig. 4 represents a section on line 4—4 of Fig. 1; Fig. 5 represents a section on line 5—5 of Fig. 1.

The same reference characters indicate 35 the same or similar parts in all of the views.

My improved saw comprises a rigid frame composed of a back 12, an outer arm 13 adapted to detachably engage the outer end of a saw blade 14, and an inner arm 15 40 carrying a strainer lever hereinafter described, said backing arm being preferably made from a single bar of steel formed as shown by Fig. 1.

To the outer end of the arm 15 is connected by a pivot pin 16 an ear 17 formed on a lever 18, the arm 15 being slotted as shown by Fig. 5 to receive the ear 17. The lever 18 has a downwardly projecting shorter arm with which the inner end of 50 the blade 14 is engaged at 19, and an upwardly projecting longer arm.

20 represents a handle adapted to be grasped by the operator and having a slot in its forward portion, the sides of said slot 55 constituting two ears 21 which bear on opposite sides of the frame. The body of the

handle is preferably made of wood and the slot is preferably provided with a metallic lining composed of side members 22 and a back member 23 formed as shown by Fig. 2. 60 The lining members are attached to each other and to the wooden body of the handle by transverse screws or rivets 24. The upper forward portions of the ears 21 are hinged to the frame by means of a pivot pin 65 or stud 25, which holds the inner sides of the ears or the lining members 22 thereof in close sliding contact with the sides of the frame, as shown by Fig. 4. The inner end of the slot or the lining member 23 therein 70 has an elongated outer surface constituting an abutment which is in sliding contact with the longer arm of the straining lever 18. Said longer arm is arranged to enter the slot and bear on the said abutment. 75 When the handle is swung from its operative position, as indicated by Fig. 2, the lever 18 is held by the blade in a position inclined relatively to the abutment, the blade being therefore loose and adapted to 80 be removed from the frame. When the handle is swung to its operative position relatively to the frame, as shown by Fig. 1, the abutment slides in contact with the lever 18 and forces said lever to the position shown by Fig. 1, its shorter arm being 85 thus moved away from the outer frame arm 13 and caused to strain the blade, the lower portions of the ears 21 of the handle being at the same time caused to bear on opposite 90 sides of the inner frame arm 15. It will now be seen that when the handle is in its operative position the lever 18 is held thereby in its straining position, the longer arm of said lever and the inner frame arm 95 15 being at the same time located in the handle slot so that the frame arm 15 supports the handle against lateral twisting movements and prevents strain on the pivot 25, the longer arm of the straining lever 18 100 being at the same time covered and securely protected against sidewise displacement.

Means are provided for securing the handle in its operative relation to the frame, said means preferably including a detent 28 105 which may be formed on the lining member 23 and is located adjacent to the pivot 16 of the straining lever, and a U-shaped latch 29, which is secured by and adapted to swing on the pivot 16, the neck portion of the latch being adapted to frictionally engage the rear side of the detent 28, as shown

by Figs. 1 and 5. When it is desired to loosen the blade, the latch 29 is swung downwardly out of engagement with the detent 28.

5 The longer arm of the straining lever 18 is preferably provided with an adjustable runner 30 adapted to bear on the elongated abutment, said runner being preferably the head of a screw, the threaded shank 31 of 10 which is engaged with a tapped orifice in the longer arm of the lever 18. By turning said screw to adjust the head or runner 30 outwardly from the edge of the lever 18 the tension imparted to the blade by the 15 described operation is increased.

It will be seen that the described construction is simple, strong and durable, and enables the blade to be quickly and tightly strained and as quickly released. The slot- 20 ted handle forming the ears 21 which bear on opposite sides of the frame and its arm 15 so that the frame supports the handle against twisting strains is an important feature of my invention, said ears also forming 25 a housing or casing for the longer arm of the straining lever. The elongated abutment at the inner end of the slot in the handle is also an important feature, said abutment adjustment applying pressure to the 30 lever moving the latter to its straining position.

Having described my invention, I claim:

1. A saw comprising a rigid frame having a back, a blade-engaging outer arm, and a 35 lever-carrying inner arm, a handle having a slot in its forward portion, the sides of which form ears pivoted to the frame and bearing on opposite sides thereof, the inner end of said slot constituting an elongated 40 abutment, a lever fulcrumed on the inner frame arm and having a shorter blade-engaging arm and a longer arm adapted to extend into said slot and bear on said abutment, the handle being adapted to swing to 45 and from its operative position relatively to the blade, and the lever being moved to a blade-straining position by the abutment when the handle is moved to its operative position, and means for confining the handle 50 in said position.

2. A saw comprising a rigid frame having a back, a blade-engaging outer arm, and a lever-carrying inner arm, a handle having a slot in its forward portion, the sides of which 55 form ears pivoted to the frame and bearing on opposite sides thereof, the inner end of said slot constituting an elongated abutment, a lever fulcrumed on the inner frame arm and having a shorter blade-engaging arm and a longer arm adapted to extend into

said slot and bear on said abutment, the handle being adapted to swing to and from its operative position relatively to the blade, and the lever being moved to a blade-straining position by the abutment when the handle is moved to its operative position, a 65 fixed detent on the handle adjacent to the fulcrum of the lever, and a latch pivoted to the inner frame arm and adapted to engage said detent to confine the handle in its 70 operative position.

3. A saw comprising a rigid frame having a back, a blade-engaging outer arm, and a lever-carrying inner arm, a handle having a slot in its forward portion, the sides of 75 which form ears pivoted to the frame and bearing on opposite sides thereof, the inner end of said slot constituting an elongated abutment, a lever fulcrumed on the inner frame arm and having a shorter blade-engaging arm and a longer arm adapted to extend into 80 said slot and bear on said abutment, the handle being adapted to swing to and from its operative position relatively to the blade, and the lever being moved to a 85 blade-straining position by the abutment when the handle is moved to its operative position, and means for confining the handle in said position, the longer arm of the lever being provided with an adjustable runner 90 contacting with the abutment whereby the tension of the blade may be regulated.

4. A saw comprising a rigid frame having a back, a blade-engaging outer arm and a lever-carrying inner arm, a handle composed of a wooden body having a slot in its forward portion forming two ears, and a metallic lining in said slot, the sides of the lining bearing on opposite sides of the frame, and a lining at the inner end of the 100 slot constituting an elongated abutment, a pivot pin connecting said ears and the sides of the lining with the frame, and a lever fulcrumed on the inner frame arm and having a shorter blade-engaging arm and a 105 longer arm adapted to extend into said slot and bear on said abutment, the handle being adapted to swing to and from its operative position relatively to the blade, and the lever being moved to a blade-straining position by the abutment when the handle is moved to its operative position, and means for confining the handle in said position.

In testimony whereof I have affixed my signature, in presence of two witnesses.

JOSEPH WOOD.
